(57) **CLAIM**

The ornamental design for a handle of a pistol-type nozzle, as shown and described.

DESCRIPTION

FIG. 1 is an upper perspective view of the handle of a pistol-type nozzle showing my design.

FIG. 2 is a front view thereof;

FIG. 3 is a back view thereof;

FIG. 4 is a side view thereof;

FIG. 5 is an opposite side view thereof;

FIG. 6 is a top plan view thereof;

FIG. 7 is a bottom view thereof;

FIG. 8 is a rear perspective view thereof;

FIG. 9 is another perspective view thereof, showing alignment of an attachment in broken lines; and,

FIG. 10 is a perspective view thereof, showing connection of the attachment of FIG. 9 in broken lines.

The portions shown in broken lines are presented for illustrative purposes only and form no part of the claimed design.
